UNITED STATES PATENT OFFICE.

ISAAC M. PEASE, OF CINCINNATI, OHIO.

BUCKLE.

Application filed May 6, 1922. Serial No. 558,939.

To all whom it may concern:

Be it known that I, ISAAC M. PEASE, a citizen of the United States, residing at Cincinnati, in the county of Hamilton and State 5 of Ohio, have invented a new and useful Buckle, of which the following is a specification.

The device forming the subject matter of this application is a suspensory, and the invention aims to provide novel means for assembling the belt and the perineal strap with the suspensory, in such a way that but 10 three fastening elements are necessary as distinguished from six, eight or more, the 15 cost of the article being cut down accordingly. Another object of the invention is to provide novel means for hingedly connecting the fasteners with the suspensory, so that an adjustment of the belt and the per- 20 neal strap may be brought about readily.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 30 and claimed, it being understood that, within the scope of what is claimed, changes in the precise embodiment of the invention shown can be made without departing from the spirit of the invention.

In the drawings:—

Figure 1 shows in plan, a suspensory constructed in accordance with the invention; Figure 2 is a section on the line 2—2 of Figure 1; Figure 3 is a section on the line 40 3—3 of Figure 1; Figure 4 is a plan of the fastener.

The numeral 1 marks a suspensory. The numeral 2 designates a plate-like fastener comprising arms 3 located at right angles 45 to each other. The ends of the arms 3 are united by a connecting bar 4. An opening 5 is formed in one arm, an opening 15 being formed in the other arm. A bar 6 extends across the opening 5 and the bar 7 extends 50 across the opening 15, the bars being formed integrally with the arms. The bars 6 and 7 are supplied on their inner edges with teeth 8. By means of stitching 9, or the like, the elements 4 of the fasteners 2 are connected

to the suspensory 1 in such a way that the 55 fasteners have a hinged mounting on the suspensory. The lower portion of the suspensory 1 carries a guide 10.

The numeral 11 designates a belt, the ends 60 of which are passed through the openings 5, and are looped as at 12 about the bars 6 of the fasteners 2. The free ends 14 of the belt are bound beneath the fasteners 2. A perineal strap 15 extends slidably through the 65 guide 10. The ends of the perineal strap 15 are passed through the openings 5 of the fasteners and are looped about the bars 7, the free ends 16 of the perineal strap 15 being bound beneath the fastener. The teeth 70 8, obviously, hold the belt and the perineal 75 strap against slipping.

It is to be observed that three elements 80 only are necessary in order to connect the belt 11 and the perineal strap 15 with the suspensory 1, to wit, the guide 10 and the 75 fasteners 2. Heretofore, as many as nine fastening elements have been used, and it is obvious that the device forming the subject matter of this application simplifies 85 the construction and cuts down the cost of manufacture. Owing to the fact that the fasteners 2 are hingedly mounted at 9—4 on the suspensory 1, a ready adjustment of the ends of the belt 11 and the perineal strap 15 may be brought about, since the fasteners 85 may be swung outwardly, away from the suspensory 1.

What is claimed is:—

A fastener of approximately triangular 90 outline and comprising long and short arms disposed at right angles to each other, and a connection uniting the outer ends of the arms, the connection being of less width than either arm, the long arm having a long opening, and the short arm having a short opening, the openings being disposed approximately at right angles to each other, and there being bars extended across the openings and disposed approximately at right angles to each other. 95

In testimony that I claim the foregoing as my own, I have hereto affixed my signature in the presence of two witnesses.

I. M. PEASE.
